DESIGN FOR A COMBINATION GAS AND COAL RANGE

Herman H. Heidbreder, Quincy, Ill., assignor to
Portland Stove Foundry Co., Portland, Maine

Application July 17, 1939, Serial No. 86,055

Term of patent 7 years

To all whom it may concern:

Be it known that I, Herman Heidbreder, a citizen of the United States and a resident of the city of Quincy, county of Adams and State of Illinois, have invented a new, original, and ornamental Design for a Combination Gas and Coal Range, of which the following is the specification, reference being had to the accompanying drawing, forming a part thereof.

Figure 1 is a perspective view of a combination gas and coal range showing my new design;

Figure 2 is a front elevational view thereof on a slightly smaller scale; and

Figure 3 is an end elevational view thereof on a slightly smaller scale.

I claim:

The ornamental design for a combination gas and coal range, as shown.

HERMAN H. HEIDBREDER.
